UNITED STATES PATENT OFFICE

2,660,201

JAW HOLDER FOR GRIPPER SHUTTLE LOOMS

Nicholas P. Darash, Cleveland, Ohio, assignor to
The Warner & Swasey Company, Cleveland,
Ohio, a corporation of Ohio

Application January 8, 1951, Serial No. 204,867

19 Claims. (Cl. 139—125)

1

This invention relates to gripper-shuttle looms, and more particularly, to thread-gripper elements for the shuttles and feeders of such looms.

An object of the invention is to improve the reliability and continuity of operation of gripper-shuttle looms.

An object of the invention is to minimize the breakage of arms of thread grippers in gripper-shuttle looms.

An object of the invention is to prevent the escape of gripper arms from gripper shuttles and feeders in the event of breakage of the arms.

An object of the invention is to prevent damage to looms due to failure of gripper arms.

In certain looms for weaving, the weft thread is carried through the shed by a gripper shuttle which is so constructed and arranged that an end of the piece of weft thread is held by the shuttle. The shuttle action is initiated at the spool side of the loom and the shuttle receives thread from a feeder element which cooperates with the shuttle to transfer the end of the thread thereto. When the shuttle arrives at the far side of the loom, the thread is released and the shuttle returned to the spool side of the loom. Shuttles and feeders useful for such purposes are shown, for example, in United States Patent No. 2,090,703 issued August 24, 1937 to R. Rossman and normally include a gripper element having extended arms which form jaws for gripping the thread. The arms of the gripper element are formed as extensions from a yoke portion and of a resilient material in a fashion such that the thread will be held by the jaws under a considerable tension.

As a result of the manner of operation of such shuttles and feeders, movement of the arms of the gripper to open and close the gripping jaws tends to fatigue the metal of which the arms are made, with the result that, after a period of time, an arm may break and the detached portion escape from the shuttle or feeder body. Such a loose piece may cause serious damage to a loom. For example, the piece may be left in the shed and cause breakage of a large group of teeth or dents of the reed. Again it may jam the shuttle conveyor so that the shuttles are not returned.

The present invention is concerned with a novel shuttle and feeder-gripper element whereby these difficulties may be largely eliminated. In carrying out the invention in accordance with one form thereof, a gripper is utilized in which the space between the arms at the yoke end is filled with rubber, or other rubber-like material. The rubber is bonded to the arms and to the yoke

2

portion, and since breakage normally occurs near the base of the arm, a broken arm is restrained from dropping out of the shuttle or feeder by the rubber insert. In an alternate form of the invention, a rivet is passed between the gripper arms and projections formed on the inner sides of the gripper arms so that, in the event of breakage, the projections engage the rivet and prevent the escape of the broken portion.

10 It is an advantageous feature of the use of the rubber insert that the fatigue effect on the gripper arms is greatly reduced and very little breakage takes place.

15 These and other objects, features and aspects of the invention will be more readily apparent from a consideration of the following detailed specification and claims, taken in connection with the accompanying drawings, in which:

Fig. 1 is a front view of a gripper-shuttle loom;
20 Fig. 2 is a cross-sectional view of the loom of Fig. 1, represented as viewed from the right side;
Fig. 3 is a vertical sectional view of the gripper shuttle of the invention;

25 Fig. 4 is a sectional view of the shuttle of the invention, taken in the direction 4—4 as indicated in Fig. 3;

Fig. 5 is a view similar to Fig. 3, but showing a partial vertical section of the alternative embodiment of the invention;

30 Fig. 6 is a partial sectional view taken in the direction 6—6 in Fig. 5;

Fig. 7 is a front elevation of a portion of the loom showing a feeder support and a thread feeder which holds the weft thread before the shuttle-gripper jaws grip the thread; and

35 Fig. 8 is a partial sectional view of the thread feeder and shuttle taken in the direction 8—8 in Fig. 7.

Referring now to Figs. 1 and 2, there is shown 40 a weaving machine of the gripper-shuttle type. The invention is of especial use and importance in such machines, which operate automatically and at high speeds. The weaving machine comprises a supporting frame including a pair of end members 21 and 22 secured to cross members 23 and 24, as shown in cross-section in Fig. 2. The machine includes a cloth beam 25 to wind a roll of cloth 26; heddle frames 27 carrying the heddles; a shedding mechanism enclosed within 45 a housing 28; and one or more stationary spools or packages 29 for the weft yarns. The machine may be provided with shuttle picking, guiding, and conveying mechanism of the general type disclosed in United States Patents No. 2,160,338,

55 2,160,339, 2,316,703 and 2,420,380 to A. Moessinger

and United States Patent No. 2,099,627 to R. Rossman.

In the apparatus represented in Fig. 1, there is an electric motor 31 for providing the driving power, which is adapted both to drive the main shaft 32 through a suitable drive, such as a belt or chain drive 33, and to drive an auxiliary shaft 34 through a suitable drive, such as a belt or chain drive 35. A hand wheel 36 may also be provided for the main drive shaft 32. In order to facilitate rapid stoppage of operating parts of the weaving machine in case of thread failure or failure of some operative part of the weaving machine, an automatically operating clutch and brake mechanism is also provided which is concealed within the drum 37, represented in Fig. 1.

Referring to Fig. 2, the weaving machine includes a warp beam 38, heddle frames 27 carrying heddle eyes 39, a picker box 41 including lay mechanism 42, and the cloth beam 25. There is a conventional supporting bar 43 carrying a plurality of drop wires 44 for an electrical stop mechanism responsive to failure of warp yarn, a stop shaft 45 represented in cross-section in Fig. 2 for producing numerous stop motions, not visible in Fig. 2, including certain conventional stop mechanisms, not described herein, and a manual control handle 46 for starting and stopping the weaving machine. The warp beam 38 is provided with a let-off mechanism comprising a gear drive including gears 47 and 48 mounted respectively on a shaft 49 and on the warp beam 38. There is a pivoted support for a whip roll 50. For removably supporting one or more warp beams for adapting the weaving machine to produce one or more widths of cloth, a supporting frame 51 is provided such as described in greater detail in my copending application, Serial No. 21,395, filed April 16, 1948, now Patent No. 2,514,152.

During the operation of the weaving machine, the warp yarns 52 are drawn from the warp beam 38 over the whip roll 50 through the drop wires 44 and formed into a shed 53 by the operation of the heddles 27 controlled by the shedding mechanism 28. They are then drawn through the dents of the reed 54 carried by the lay mechanism 42 along conventional rolls 55 to the cloth beam 25, in the form of cloth 56. As in conventional gripper-shuttle weaving machines, the weft threads thrown through the shed 53 by the mechanism in the picker box 41 are beaten in by the reed 54 to form the cloth.

Referring now to Figs. 3 and 4, the shuttle of the invention includes a body or holder 57 of generally elongate form and having separated, parallel top and bottom portions 58 and 59. At the lead end of the shuttle, the side walls 60 of the shuttle body meet the top and bottom to form an arcuate, tapered nose 61. The trailing end of the shuttle is open while the top and bottom have rectangular apertures 62 and 63 formed therein.

Fitted within the shuttle body is a gripper 64 including a yoke portion 65 and arms 66 and 67, the entire piece being formed of a tough resilient material such as spring steel. The yoke portion is secured to the shuttle body by means such as rivets 68 which extend between the top 58 and bottom 59 and hold the gripper securely in place. The arms 66 and 67 are formed into jaws 69, the disposition of the arms being such that the jaws are normally closed under a predetermined tension of the arms. Openings 70 and 71 in the top and bottom of the shuttle body

permit the introduction of a jaw actuating member of the loom which may bear against the projections 72 and 73 to open the jaws.

In accordance with the invention, an insert 74 of rubber-like material is fitted between the arms at the yoke end of the gripper and bonded to the surfaces of the arms or to the arms and yoke. The insert may be of a length suitable for the particular use, while the proportions indicated in the drawing have been found satisfactory in one application. A properly resilient material must be used and the term "rubber-like" is intended to include natural rubber, synthetic rubber, and other materials having physical properties such as resilience similar to those of rubber. Any suitable process may be utilized for bonding the resilient material to the surfaces of the yoke and arm portions of the gripper. As used herein, the term "bonded" is a generic term intended to include any means whereby rubber or rubber-like material may be joined or attached to other, and particularly metallic, materials.

Referring now to Figs. 5 and 6, there is illustrated an alternative embodiment of the shuttle of the invention. As there shown, in partial view, the shuttle body is similar to that of Figs. 3 and 4, while a modified form of gripper 75 is enclosed therein. The gripper includes a yoke 76 and two arms 77 and 78 just as the first gripper 64. The arms 77 and 78 are, however, formed with two inwardly-directed projections 79 and 80. These projections are of such length that they do not interfere with the movement of the jaws and that they do not normally come into action with proper operation of the gripper and the shuttle. However, if an arm should break near its base at the yoke, the projection engages a pin 81 extending between the top and bottom 40 of the shuttle body. The broken arm is thus constrained by the pin and a side wall 60 so that it cannot escape from the trailing end of the shuttle. The pin 81 may, of course, be any suitable rivet, bolt or stud-like projection.

Referring now to Fig. 7, there is shown a thread feeder, constructed in accordance with the invention as previously set forth with respect to the shuttle. The thread feeder is mounted in a firing box indicated generally at 82, and serves to transfer thread from the spools 29 to the shuttle, the thread transfer or feed position of the shuttle being shown in Fig. 7. In operation, the shuttle is projected between the firing box 82 and a receiving box indicated generally at 83.

As shown in Figs. 7 and 8, the thread feeder includes a support member or body 84, and a thread gripper 85. The support member includes a plate-like piece 86 and pieces 87, 88 and 89 ancillary thereto which serve to secure and guide the thread gripper. The thread gripper 85 comprises a yoke portion 90 and spaced resilient arm portions 91 and 92 similar to the gripper of the shuttle previously described, and differing only in detail therefrom. The gripper is supported at the yoke portion by pins or rivets 93 extending through the pieces 86 and 87 and the yoke portion 90. The pieces 88 and 89 are formed so as to be spaced apart from the support plate and serve as a constraint and guide for the gripper arms 90 and 91.

An insert 94 of rubber-like material is fitted between the arms 90 and 91 at the yoke end of the gripper and bonded to the surface of the arms or to the arms and the yoke. This insert 75 functions identically the same fashion as that

of the shuttle gripper previously described and the considerations there set forth are pertinent here.

In operation, the thread feeder jaws 91 and 92 are normally closed to hold the thread 95 in an operative position. The jaws of a shuttle 93 are positioned at an angle of 90° with respect to those of the feeder and are spread by an actuating or control member 97. The shuttle-gripper jaws then pass the jaws 90 and 91 of the feeder and, upon withdrawal of the member 97, the shuttle jaws seize the thread 95. A feeder jaw actuating or control member 98 then separates the jaws 90 and 91 and the shuttle is projected from the firing box carrying the thread with it. It will thus be apparent that the rapid actuation of the feeder will be accompanied by severe vibrational strains in the gripper arms and that the present invention may serve to mitigate those strains and lengthen the life of the feeder gripper.

It is an important result of the use of the rubber-like insert, in the preferred form of the invention, that breakage of the arms is virtually absent. It is believed, although this is only a hypothesis, that the rubber serves as a damper and cushions the vibrations in the arms, and particularly those of a relatively high frequency which might tend to cause a rapid fatiguing of the metal.

It is to be understood that the specific nature of the present disclosure is not intended to be restrictive or confining and that various rearrangements of parts and modifications of design may be resorted to without departing from the scope or spirit of the invention as herein claimed.

What is claimed is:

1. A shuttle for looms comprising a body having generally parallel top and bottom portions, one end of said body being open, a gripper in said body comprising a yoke portion, spaced arms extending from said yoke portion to form jaws, means securing said gripper portion to said body, and means attached to said gripper arms for constraining arms which become separated from the yoke portion.

2. The invention in accordance with claim 1, said constraining means comprising a piece of rubber-like material bonded to said yoke and to said arms.

3. The invention in accordance with claim 1, said constraining means comprising projections extending inwardly from the arms.

4. A shuttle for looms comprising a body having separated top and bottom portions, a gripper disposed between said top and bottom portions, said gripper comprising a yoke portion and extended arm portions, restraining means for said gripper comprising pin-like members extending between said top and bottom portions and means attached to said gripper arms for constraining arms which become separated from the yoke portion.

5. The invention in accordance with claim 4, said constraining means comprising an insert of rubber-like material bonded to the arms at the yoke end thereof.

6. The invention in accordance with claim 4, said constraining means comprising projections extending inwardly from the arms.

7. A shuttle for looms comprising a shuttle body, a gripper in said shuttle body comprising a yoke portion and extended oppositely disposed arm portions, means securing the gripper to the shuttle body and means for restraining broken

gripper arms comprising a piece of rubber-like material bonded to the arms of the said gripper.

8. A shuttle for looms comprising a body having generally parallel top and bottom portions, one end of said body being open, a gripper disposed between said top and bottom portions comprising a yoke portion and oppositely disposed arm portions extending therefrom, means securing the gripper to the body, and means for restraining broken gripper jaws within the shuttle body comprising inwardly extending projections on said arms and a pin-like piece extending between the top and bottom portions of the shuttle body and being disposed between the gripper arms at a point between the projections and the open end of the shuttle body.

9. A shuttle for looms comprising a body having generally parallel top and bottom portions, spaced side portions extending between the top and bottom portions, a gripper disposed between said body portions, and comprising a yoke portion and spaced arm portions extending therefrom, means securing the gripper to the body and means for restraining broken gripper jaws within the body comprising projections on the arms and a member attached to the body whereby the projection prevents the escape of the arms from between the side and the member.

10. Thread gripping apparatus for looms comprising a body, a gripper associated with said body comprising a yoke portion and spaced resilient arm portions forming gripper jaws, means securing the gripper to the body, and an insert of rubber-like material bonded to the gripper arms at the yoke end thereof.

11. In a loom, the combination of a support member, a gripper comprising a yoke portion and spaced resilient arm portions, means securing the gripper to the support member, and means attached to the gripper arms for constraining gripper arms which become separated from the yoke portion.

12. The invention in accordance with claim 11, said last named means comprising a piece of rubber-like material bonded to the arm portions.

13. The invention in accordance with claim 11, said last named means comprising an insert of rubber-like material fastened to the arm portions and the yoke portion.

14. A thread gripper for looms comprising a yoke portion, oppositely disposed arms extending from said yoke forming gripper jaws, and a piece of rubber-like material attached to said jaws at the yoke end thereof.

15. A thread gripper for looms comprising a yoke portion, oppositely disposed arms extending from said yoke forming jaws, and a piece of rubber-like material bonded to said yoke and to said jaws.

16. A thread gripper for looms comprising a yoke portion, oppositely disposed arms extending from said yoke forming gripper jaws, and inwardly extending projections on the inner sides of said arms.

17. A thread gripper for looms comprising a yoke portion, oppositely disposed arms extending from said yoke forming gripper jaws, and oppositely disposed projections on said arms.

18. Thread gripping apparatus comprising a body having top and bottom portions, one end of said body being open, a thread gripper in said body comprising a yoke, and spaced arms extending from said yoke to form jaws, means securing said thread gripper to said body, and means

extending between the gripper arms for constraining arms which become separated from the yoke.

19. Thread gripping apparatus comprising a body having two spaced portions, one end of said body being open, a thread gripper disposed between said spaced portions comprising a yoke, spaced arms extending from said yoke to form jaws, means securing said gripper to said body, and means in the space between the gripper arms for constraining an arm which may become separated from the yoke.

NICHOLAS P. DARASH.
